CENTER STOP MOTION FOR LOOMS

Filed Jan. 10, 1938

FIG. 1

UNITED STATES PATENT OFFICE

2,141,636

CENTER STOP MOTION FOR LOOMS

George E. Adams, Pawtucket, R. I., assignor to
Crompton & Knowles Loom Works, Worcester,
Mass., a corporation of Massachusetts

Application January 10, 1938, Serial No. 184,210

2 Claims. (Cl. 139—376)

This invention relates to improvements in filling stop motions for looms and it is the general object of the invention to provide a construction whereby the shock incident to the knocking-off operation of the loom will not be transmitted to the detector fingers of the stop motion.

In center stop motions more particularly the kind used for finer fabrics it is customary to pivot a set of tines on the lay in front of the shuttle path. The knock-off dagger projects forwardly from the lay and moves toward a notched knock-off collar on a roll rod extending under the breast beam and connected to the shedding mechanism. When the fork drops into a well in the lay due to absence of weft the dagger is raised to engage the collar. During rolling of the shaft the dagger is suddenly released from the notch and snaps away with an abrupt downward motion.

As heretofore constructed the link which causes the fork to rise and fall has been pivoted directly to the dagger carrying lever so that any motion of the dagger is communicated to the fork. It has been found that the aforesaid quick motion of the dagger away from the notched collar causes the fork to snap upwardly against the fell of the cloth. When the fabric being woven is delicate it is injured by this unnecessary movement of the fork.

It is an important object of my present invention to provide a connection between the dagger and the fork which shall be positive in one direction but yieldable in the opposite direction, the yielding occurring when the dagger snaps down from the notched collar so that its motion will not be communicated to the fork. The fabric is thereby spared the injury incident to the operation of old forms of link.

On a well-known type of center stop motion for light fabric looms it is customary to raise the fork by a rod which is caused to move upwardly relatively to the lay when the latter moves rearwardly, this motion also depressing the dagger. As the lay moves forwardly there is a relative downward motion of the rod so that the fork falls and the dagger rises by the action of a light spring. It is a further object of my present invention to apply the force of this rod directly to the link and permit the dagger to have a motion independent of the link. The force from the rod may be transmitted through an enlarged head formed on the bottom of the link and serving as a stop for the dagger carrying lever.

With these and other objects in view which will appear as the description proceeds, my invention resides in the combination and arrangement of parts hereinafter described and set forth.

In the accompanying drawing, wherein a convenient embodiment of my invention is set forth,

Fig. 1 is a longitudinal vertical section through a portion of a loom showing my improved form of stop motion applied thereto with the lay in rear position and the fork raised preparatory to a detecting operation.

Fig. 2 is a view similar to Fig. 1, but with the lay forward and the fork in stopping position due to absence of weft, the motion of the dagger relative to the link being indicated in dotted lines, and

Fig. 3 is a horizontal section on line 3—3 of Fig. 1.

Referring to the drawing, the loom frame 10 has a breast beam 11 along the under side of which extends a rolling rod 12 to which is secured a collar 13 having a knock-off notch 14. A shoulder 15 above and behind notch 14 is formed on the collar to engage dagger D near the end of the knock-off stroke. It is necessary for the dagger to enter notch 14 before the lay reaches front center and the lay continues to advance after the rod 12 is fully turned, due to slippage of the brake. The purpose of shoulder 15 is to free the dagger from the notch so the lay can continue to move forwardly without breakage. The unseating of the dagger from the notch is followed immediately by a quick downward motion of the dagger, this motion being caused by shoulder 15.

The lay L has a reed 16 along which a shuttle S travels between the upper and lower warp sheds W and W', respectively. The cloth C has a fell F which lies at the forward limit of motion of the reed.

Secured to the front face of the lay is a bracket 20 having a bearing 21 in which is journaled a shaft 22. The latter has fastened thereto a plate 23 and a link 24 has a rod head 25 pivoted on a pin 26 secured in the plate 23. The times of the filling fork 30 are secured in the conventional manner to a barrel 31 secured to the shaft 22. The lay has a well 32 into which the fork 30 can fall when weft is absent.

The bracket 20 has a forwardly extending arm 35 carrying a stud 36 on which is pivoted a dagger carrying lever 37 from the forward end of which projects the dagger D held in adjusted position by a set screw 39. A light torsion spring 40 has the outer end thereof secured to the stud 36 and has the inner end extended rearwardly as at 41 to lie over a lug 42 on a rearwardly extending arm 43 of lever 37.

A depending guide 45 on the bracket 20 receives the upper end of a pump rod 46, the lower end of which not shown moves about a pivot behind the axis of the lay, as shown in Knowles Patent 376,774. As a result of this relation rearward motion of the lay will cause a relative upward motion of rod 46, while forward motion of the lay will cause a relative downward motion of

said rod 46, the latter motion corresponding to and permitting the detecting or falling stroke of the fork 30. When the rod 46 is down spring 40 lifts the dagger so that it can enter the notch 14 should weft be absent.

The matter thus far described may be constructed substantially as heretofore, the rod 46 rising and falling relatively to the lay as the lay moves backwardly and forwardly and the notch 14 being positioned for engagement with the dagger which is normally urged to enter the notch by spring 40. For a further description of a center stop motion having characteristics already described reference may be had to McGuiness Patent No. 1,223,708. If made according to both the Knowles and McGuiness patents and as used generally in the industry, the lower end of the link 24 would be pivoted directly to the arm 43, but in that construction the quick downward motion of the dagger as it leaves the notch 14 would cause an abrupt upward motion of fork 30 against the fell F of the cloth.

My invention aims to eliminate the direct pivotal connection between the link and the dagger carrying lever and the substitution therefor of the connection which permits the positive transmission of forces upwardly to raise the fork and lower the dagger, but in which the arm 43 may rise relatively to the link when the latter is down. These results I accomplish by forming the rear end of arm 43 with a slot 50 through which extends the lower end of the link 24. A head 51 preferably formed integrally with the link 24 lies under the arm 43 in a position to receive the upward thrust of rod 46. A lay carried stop 60 may be positioned to engage the top of arm 43 to limit downward motion of the forward end of the dagger so that the same may not engage the take-up roll not shown.

In the operation of my invention upward thrust of rod 46 elevates head 51 and link 24, thereby raising fork 30 and depressing dagger D to the position shown in Fig. 1. As the lay moves forwardly the relative downward motion of rod 46 permits the spring 40 to lower arm 43 and raise the dagger. This downward motion of arm 43 acts through head 51 to lower the link 24 and thereby require the fork 30 to move toward the well 32. If sufficient weft is present the fork will be arrested in its downward motion and head 51 will be stopped at some point above its lowest possible position corresponding to a location of the dagger at a distance below the collar 13 to avoid contact therewith. Should weft be absent, however, the fork and link 24 will continue to descend and the spring will raise the dagger so that it will enter the notch 14. Head 51 acts as a stop for the dagger, and a pin 70 fixed on bracket 20 engages shoulder 61 of disk 23 to limit down motion of the link. The dagger is thus positioned to enter notch 14. As the lay moves forwardly the dagger rocks collar 13 and shaft 12 in a clockwise direction as viewed in Fig. 1 to stop the loom. Shoulder 15 kicks the dagger down from the full to the dotted line position of Fig. 2 as already described. This motion can occur without being transmitted to the fork inasmuch as the arm 43 is free to rise above the head 51 as shown in dotted lines in Fig. 2 without causing upward motion of either the link 24 or the fork 30. The fell of the cloth is therefore spared the abrasion which has formerly attended the stopping of the loom and growing out

of the fact that the lower end of link 54 has previously been pivoted directly to the lever 37.

From the foregoing it will be seen that I have provided simple means for coupling the filling fork and the dagger in such a way that both can be controlled by the rod 46 preparatory to a detecting operation, but that after the detecting has been completed and the dagger is in contact with the collar 13 the dagger can move down without disturbing the filling fork in the well.

Having thus described my invention it will be seen that changes and modifications may be made therein by those skilled in the art without departing from the spirit and scope of the invention and I do not wish to be limited to the details herein disclosed, but what I claim is:

1. In a filling stop motion for a loom having a lay, a filling fork pivoted to the lay, loom stopping mechanism, a pivotally mounted collar forming part of the stopping mechanism and having a notch and a shoulder at one side of the notch movable in a direction toward the notch during a loom stopping operation, a dagger carried by the lay to enter the notch and cause pivoted motion of the collar on loom stopping operations and causing the shoulder to move against the dagger to dislodge the latter from the notch, an actuator moving in one direction as the lay moves rearwardly and moving in the opposite direction as the lay moves forwardly, a link moving with the filling fork and having a head on the end thereof remote from the fork for engagement with the actuator, and an arm moving with the dagger bearing against that side of the head opposite the actuator, said arm being movable away from the head independently of motion of the link when said shoulder dislodges the dagger from the notch.

2. In a filling stop motion for a loom having a reciprocating lay, a filling fork pivoted to the lay for vertical motion relatively to the latter, a link connected to the filling fork movable vertically with respect to the lay to cause movement of the filling fork, a head formed on the lower end of the link, an actuator for the link having a motion upwardly relatively to the lay to engage the head and cause lifting of the link and fork as the lay moves rearwardly, said actuator movable downwardly relatively to the lay as the latter moves forwardly and the fork and link being capable of downward motion relatively to the lay as the latter moves forward, a dagger pivoted to the lay and having an arm to bear against that part of the head opposite the actuator, loom stopping mechanism including a collar having a notch therein and a shoulder at one side of the notch, the dagger to enter the notch on stopping beats of the loom to cause movement of the collar and said shoulder movable against the dagger to dislodge the latter from the notch, said arm being movable away from the head independently of the link when the dagger is dislodged from the notch by said shoulder, and resilient means acting upon the dagger and arm tending normally to move the dagger toward position for engagement with the notch of the collar and also normally exerting a force on the head in a direction toward the actuator to cause downward motion of the fork relatively to the lay when the actuator has a downward motion relatively to the lay on forward beats of the latter.

GEORGE E. ADAMS.
